ALFRED T. BROWN, OF CINCINNATI, OHIO, ASSIGNOR TO THE WARNER ELEVATOR MFG. COMPANY, OF CINCINNATI, OHIO, A CORPORATION OF OHIO.

DASH-POT BUFFER.

1,267,626.

Specification of Letters Patent. Patented May 28, 1918.

Application filed April 2, 1917. Serial No. 159,820.

To all whom it may concern:

Be it known that I, ALFRED T. BROWN, a citizen of the United States, and residing at Cincinnati, in the county of Hamilton and State of Ohio, have invented a new and useful Improvement in Dash-Pot Buffers, of which the following specification is a full disclosure.

My invention relates to a heavy duty buffer adapted to elevator usage and the like, to be placed near the end of the path of travel of a ponderous body, to cushion the final movement and bring the body to rest without shock or jar.

As is common in devices of this character, a cylinder and piston arrangement is employed, the resistance agency being combined tension mechanism and the fluid to be displaced from one side to the other of the moving piston by passing around and through said piston during its reciprocating movements.

The objects of the invention are to provide the maximum resistance with a comparatively short piston structure, to effectively guide the spring; to provide structures and arrangements controlling the oil displacement flow under the influence of the moving piston, and to constitute a buffer strong enough for this heavy duty, durable, efficient, automatic and wholly reliable, so as to insure safety as well as superior buffering function.

The features of the invention will be more fully set forth in the description of the accompanying drawings, forming a part of this specification, wherein.

Figure 1 is a central vertical section showing the piston compressed into the cylinder under buffering conditions.

Fig. 2 is a similar view of the device in normal position, i. e. piston relaxed.

Fig. 3 is a plan section of the buffer on line 3—3, Fig. 1.

The cylinder is upright and bolted on base 1, the lower portion of the cylinder has the circumferential portion 2, extending from line x—x to the base and from this line the cylinder is internally tapered or

upwardly flared, this taper cylinder portion 50 terminating at line z—z, representing the upper or normal piston position. Above line z—z, the cylinder is widened out to constitute an oil displacement chamber 6, having the cylinder head 7 orificed for the piston 55 rod. The piston rod 8 is hollow and the piston 9 fits the circumferential cylinder portion 2 and has a valve 10, held normally closed when the piston drops by means of valve stems 11 and coil springs 12, and 60 opening when the piston retracts to flow oil from the displacement chamber back into the dash-pot or cylinder. The hollow rod 8 extends through the piston, thus communicating with the holder through the 65 piston, constituting a piston chamber having a restricted communication with the holder, whereby the oil offers resistance to the piston movement in the direction of spring compression.

To center the piston, guide it and enable tension means to be effectual, combined with the oil resistance, I provide the following instrumentalities:

A concentric guide rod or post 13 is secured in the base 1 and it passes upwardly centrally through the piston and hollow piston rod, terminating, preferably, just above line z—z, in the lower end of the displacement chamber 6.

Also, preferably, a guide sleeve 14 projects concentrically downwardly from the cylinder head 7, terminating near the line z—z, and forms an external guide for the hollow piston rod, a rod 13 fixed to the base 85 projects into the hollow piston rod and forms an internal guide for the spring 15, which is housed within the piston rod as the piston descends in its cylinder. This coil spring extends from base 1 to the screw thread adjustable plug 16 in the upper end of the hollow piston-rod. Above plug 16 is preferably a spring bumper 17 for cushioning the initial contact of elevator member 18. In order to return to the cylinder, the oil which 95 works up between the interior of the guide sleeve 14 and the exterior of the hollow piston rod 8, I provide orifices 19 in the upper

end of this guide sleeve. With the buffer ready for operation, and oil in the cylinder portions 2 and 4 (Fig. 2), the member to be cushioned (*i. e.* elevator or weight) engages the end of the piston rod and forces the piston downwardly into the tapering portion of the cylinder, simultaneously compressing the piston rod spring and displacing the oil around the piston periphery, whence it escapes into the upper chamber 6. Of course the oil will offer less resistance at the beginning of the piston movement because the oil will escape more freely around the piston at the larger diameter portion of the taper cylinder bore, gradually escaping with more difficulty as the piston descends, and so operating to rapidly increase the resistance to provide any desired degree of cushioning or braking force in a relatively short dimension of piston or elevator movement. When the piston reaches line $\alpha-\alpha$, where the cylinder circumferentially fits the piston, the greatest resistance will be offered. The oil being forced upwardly into the space between the post 13 and the hollow piston rod and around the coil spring, will also work in between the guide sleeve and piston-rod, thus thoroughly oiling all the moving elements, rendering the cushioning effect smooth and uniform.

When the piston has reached the end of its buffer movement, the coil spring is not fully compressed, coil on coil. The coil spring is supported and guided throughout the length, and a compact cylinder and piston are provided with a length of travel adequate to give efficient buffer operation. When the elevator or weight is raised, the spring raises the piston, the oil flowing back through the piston valves into the dash-pot cylinder portions 2 and 4.

Having described my invention, I claim:—

1. In a device of the class described, a fluid holder having a cylindrical portion at one end and a conical portion communicating therewith, a piston reciprocal therein, a hollow piston rod communicating through the piston with the fluid holder, a concentric guide post secured within the holder and passing through the piston into the hollow rod, a coil spring within the piston rod surrounding said guide post, and adapted to move the piston in one direction, an external guide sleeve in the upper portion of the holder for the piston rod, and means for freely flowing the fluid from one side of the piston to the other during the spring actuated piston stroke.

2. In a device of the class described, a fluid holder having a cylindrical and a conical portion, a piston fitting the circumferential portion, a hollow piston rod, a guide post secured to the holder and extending through the piston into the hollow rod, a coil spring surrounding said post, extend-

ing through the rod and adapted to move the piston in one direction, and means causing the fluid to offer resistance to the piston movement when the spring is being compressed, and to flow freely from one side of the piston to the other when the piston is spring actuated.

3. In a device of the class described, a fluid holder, a piston, a hollow piston rod communicating with the holder through the piston, a coil spring in the rod extending from the base of the holder to the top of the rod adapted for moving the piston in one direction, and means providing a restricted fluid escape during the compressing movement of the piston, and for freely returning the fluid to normal position in the holder during the spring actuated movement of the piston.

4. In a device of the class described, a fluid holder having a cylindrical portion at one end and a conical portion communicating therewith, a piston reciprocal therein, a hollow piston rod communicating through the piston with the fluid holder, a coil spring with in the piston rod adapted to move the piston in one direction, and means for freely flowing the fluid from one side of the piston to the other during the spring actuated piston stroke.

5. A combined fluid and spring resistance buffering device comprising a fluid cylinder, reciprocating piston, and hollow piston rod, a spring for moving the piston in one direction, there being restricted fluid communication around the piston and through the piston into the hollow piston rod, and means providing a relatively unrestricted return passage for the fluid when the piston is spring actuated.

6. A combined fluid and spring resistance buffering device comprising a fluid cylinder and a reciprocating piston, a hollow piston rod communicating with the cylinder through the piston, a guide post in the cylinder extending through the piston into the hollow piston rod, a spring centered on said post and extending from the end of the cylinder to the other end of the hollow piston rod, there being restricted fluid communication from one side of the piston to the other during a portion of the piston spring compressing stroke, and means providing a relatively unrestricted return for the fluid when the piston is spring actuated.

7. In a device of the class described, a cylinder, a piston reciprocal therein, the cylinder having a fluid overflow portion projected beyond the normal piston position, a hollow piston rod, a guide-post in the cylinder extending into the hollow piston rod, and a coil spring supported on the guide post and extended into the piston rod for moving the piston to normal position.

8. In a device of the class described, a cyl-

inder, a piston reciprocal therein, a hollow piston rod, a guide-post in the cylinder extending into the hollow piston rod, and a coil spring supported on the guide post and extended into the piston rod for moving the piston to normal position.

5 In witness whereof, I hereunto subscribe

my name, as attested by the two subscribing witnesses.

ALFRED T. BROWN.
